UNITED STATES PATENT OFFICE.

WILLIAM F. GAMMETER, OF CADIZ, OHIO.

STOCK-SHELL FOR WINDING FABRICS.

1,332,329.

Specification of Letters Patent.

Patented Mar. 2, 1920.

Application filed May 23, 1919. Serial No. 299,127.

To all whom it may concern:

Be it known that I, WILLIAM F. GAMMETER, a citizen of the United States, residing at Cadiz, in the county of Harrison and State 5 of Ohio, have invented certain new and useful Improvements in Stock-Shells for Winding Fabrics, of which the following is a specification.

This invention relates to stock or calender shells such as are employed for winding fabrics and is designed more particularly as an improvement on the shells shown in my prior Patents No. 1,003,593 issued September 19, 1911 and No. 1,104,296 issued 15 July 21, 1914.

At the time my original calender shells were designed and patented the load of fabric and rubber wound thereon did not usually exceed from one hundred and fifty 10 to two hundred and fifty pounds and these structures were well adapted to accommodate and sustain such a load. However, present day demands necessitate the winding upon the rolls of as much as two thousand pounds or more of fabric and rubber. 20 It is desirable and customary to mount these rolls upon mandrels relatively small in diameter and in fact the greater portion of such rolls are supported upon mandrels not 25 more than one and a quarter inches in cross sectional dimensions. Of course, where such a mandrel is of any considerable length, there is likely to be a deflection or yielding of the mandrel in proportion to the load and 30 the length of the mandrel. This disadvantage was to some extent overcome in the structure shown in my Patent No. 1,104,296 by the provision of a tube fitting the heads of the shell and fitting the mandrel, but I 35 have found that even this arrangement is not entirely effective in preventing sagging or deflection of the mandrel where such extraordinarily heavy loads are imposed upon the shell. The present invention therefore 40 has as one of its objects to provide a shell so constructed that the load imposed upon the body of the shell will be evenly distributed and sustained throughout the length of the mandrel so that without being required to replace the mandrels now in use 45 by mandrels of greater cross sectional dimensions, I am enabled to adapt the rolls to receive the extraordinary weight imposed 50 upon them under present demands of manu-

facture, without deflection or sagging of or 55 other injury to the mandrel.

The calender shells are provided within their ends with heads constructed to fit the mandrel for supporting the shell and in my previously patented structures the peripheries or rims of these heads had only a short bearing in the respective ends of the shell so that they were liable to become broken out, which was, of course, a great disadvantage. The present invention therefore has 60 as a further object to provide these heads with a bearing of maximum length within the respective ends of the shell so as to the more effectually brace the shell at its ends and more securely anchor the heads in the 65 ends of the shell.

Another object of the invention is to provide such a shell with a mandrel tube representing an improvement over the tube employed for example in my Patent No. 75 1,104,296.

In the accompanying drawings:

Figure 1 is a perspective view of one end of a calender shell constructed in accordance with the present invention, a portion 80 of the body of the shell being broken away;

Fig. 2 is a perspective view looking at the inner end of one of the heads for the shell and illustrating in dotted lines the corresponding end of the mandrel tube;

Fig. 3 is a perspective view of one of the reinforcing and bracing units employed within the shell at spaced intervals along the mandrel tube;

Fig. 4 is a vertical longitudinal sectional view through one end of the shell, the respective head and the respective end of the mandrel tube, a portion of the mandrel being shown in elevation;

Fig. 5 is a perspective view of one end of the mandrel tube.

In the drawings, the numeral 1 indicates in general the body of the shell which is of the usual cylindrical form and is provided with the usual longitudinally extending slot or groove 2 to receive the edge of the fabric to be wound upon the shell, the usual strip 3 being arranged within the shell inwardly of this groove as in my previously patented structures. In itself, the body of the shell is of the previously patented construction and the improvements, as indicated above,

reside in the heads for the shell, the mandrel tube, and the means provided at intervals along the tube for bracing the walls of the shell and equally distributing the 5 load.

One of the heads above referred to is clearly shown in Figs. 1, 2 and 4 of the drawings and indicated by the numeral 4 and the said head comprises a substantially 10 cylindrical rim or body portion 5 provided at its outer end with a circumscribing shoulder 6 to abut against the end of the body of the shell when the rim or body 5 of the head is fitted into the said end of the shell as 15 shown in Fig. 4 of the drawings. The body of the head is as above stated cylindrical except that it is provided with a depressed portion 7 to accommodate the strip 3. The head 4 is formed with an integral web portion 8 having ventilating openings 9 and provided centrally with an opening 10 of a diameter and contour to snugly receive the mandrel for the shell which mandrel is indicated by the numeral 11 and is as illustrated 20 in the drawings rectangular in cross section as in the previously patented structures. By reference to Fig. 4 of the drawings it will be observed that the web 8 of the head 4 is located in a plane substantially midway 25 between the inner and outer ends of the rim or body 5 of the said head whereas in the prior structures the corresponding web was located directly at the inner end of the rim or body of the head and the head was of 30 minimum length. Thus in the present improved construction the rim or body of the head extends inwardly from the plane of the web as well as outwardly from said plane so that when fitted within the respective 35 end of the shell, it affords a bearing of maximum length.

The web 8 of each head is provided with an integral socket located centrally upon its inner face and indicated in general by the 45 numeral 12, the socket having its walls arranged in the form of a rectangle so as to receive the corresponding end of the mandrel tube and the inner faces of the walls occupying planes spaced from the respective 50 walls of the opening 10 a distance substantially equal to the thickness of the walls of the said mandrel tube so as to provide shoulders 13 the purpose of which will be presently explained. Also for a purpose to 55 be presently explained the socket 12 is formed at diametrically opposite points and in corners between adjacent walls with slots 14. As stated above the socket 12 projects inwardly from the web 8 of the respective 60 head and is consequently surrounded by that portion of the body or rim 5 of the head which extends between the periphery of the web and the inner end of the said head. Also as above pointed out, the web 8 is not 65 located at the extreme inner end of the

head but at a point substantially midway between the ends of the head and therefore when load is imposed upon the shell there will be less and in fact practically no likelihood of overturning or breaking out of the 70 head.

The mandrel tube heretofore referred to is clearly shown in Fig. 5 of the drawings and is indicated in general by the numeral 15, the said tube being preferably formed 75 from a single piece of sheet metal bent to rectangular form and having its edge portions bent at an angle to provide flanges 16 which meet at one corner of the tube and which are riveted or otherwise secured together, as indicated by the numeral 17. This tube is of cross sectional dimensions to snugly seat at its ends in the sockets 12 provided for its reception upon the heads 4, the flanges 16 engaging in one or another of 80 the slots 14 in the walls of the said sockets as shown in Fig. 2 of the drawings. As clearly illustrated in Fig. 4 of the drawings, the mandrel 11 is snugly fitted within the tube 15, the ends of the tube abutting against 85 the shoulders 13 and the ends of the mandrel extending beyond the ends of the tube and through the openings 10 in the respective head 4 so as to provide terminal journals (not shown) whereby the shell may be 90 rotatably mounted.

In order to brace the walls of the shell 1 against collapse and in order to evenly distribute along the mandrel the weight disposed upon the shell, a number of reinforcing heads of the form shown clearly in Figs. 1 and 3 of the drawings are provided. Each of these heads, indicated in general by the numeral 18, comprises a substantially circular body 19 provided with a 100 peripheral laterally projecting flange 20 which is cylindrical except for a depression 21 to correspond to the depressions 7 in the heads 4 for the purpose of seating the strip 3. The reinforcing heads 18 at their 105 flanged peripheries are of a diameter to fit snugly within the shell 1 being driven or otherwise forced frictionally into the shell. A number of these heads 18 are provided and the heads are arranged at suitable intervals throughout the length of the mandrel tube 15, each head being formed centrally with a rectangular opening 22 to snugly receive the said mandrel tube and the walls of the opening being formed at 110 their corners with notches or recesses 23 either of which may receive the flanges 16 of the said mandrel tube. Likewise the circular body of each head 18 is formed with one or more ventilating openings 24 which, 115 as in the case of the openings 9 in the heads 4, provide for the circulation of air through the shell so that the heat will be effectually carried off.

It will be evident from the foregoing de- 120

130

scription of the invention that the heads 4 have a bearing of maximum length in the ends of the shell to be supported and consequently are not liable to become broken out 5 or pried loose. Also it will be evident that the heads 18 serve effectually to prevent collapse of any portion of the shell body and likewise serve to transmit and distribute the weight imposed equally through-
10 out the length of the mandrel tube 15 from which it is transmitted to the mandrel 11. Consequently, there will be no likelihood of sagging or deflection of the mandrel even though an extraordinary weight be imposed
15 thereon. It will also be evident that the mandrel tube 15 in the particular form illustrated in the drawings, may be manufactured readily at a low cost inasmuch as it is formed up from a single piece of sheet
20 metal bent to the required shape and closed in the manner shown and described.

Having thus described the invention, what is claimed as new is:

1. In a calender shell, opposite mandrel
25 heads each including a web having a sup-
porting flange extending on either side
thereof, and a shell body receiving the en-
tire flange width of each of said heads to
30 prevent breaking out of the heads due to
overloading.

2. In a calender shell, opposite mandrel

heads each including a web having a shell
supporting flange extending on either side
thereof and a peripheral stop bead on one
edge of each flange, and a mandrel shell 35
receiving the width of each flange to the
stop bead whereby breaking out of the heads
due to overloading is prevented.

3. In a calender shell, opposite mandrel
heads each including a web having a sup- 40
porting flange extending on either side
thereof, a shell body receiving the entire
flange width of each of said heads, a hub
on each head extending inwardly of the
shell and forming mandrel tube receiving 45
sockets, and a mandrel tube fitting said
sockets.

4. In a calender shell, opposite mandrel
heads, each including a web having a sup- 50
porting flange extending on either side
thereof, a shell body receiving the entire
flange width of each head, a hub on each
head forming mandrel tube receiving sock-
ets, a mandrel tube fitting said sockets, and 55
spaced intermediate supporting members
carried on said mandrel and engaging the
inner surface of the body.

In testimony whereof I affix my signature.

W. F. GAMMETER. [L. s.]
